INVENTOR:

Fig. I James T. Stoddard,
BY

Joseph F. Schenck
ATTORNEY.

UNITED STATES PATENT OFFICE.

JAMES T. STODDARD, OF PORTLAND, OREGON.

REFUSE BURNER.

1,421,741.

Specification of Letters Patent.

Patented July 4, 1922.

Application filed September 20, 1917. Serial No. 192,276.

To all whom it may concern:

Be it known that I, JAMES T. STODDARD, a citizen of the United States of America, residing at Portland, in the county of 5 Multnomah, in the State of Oregon, have invented certain new and useful Improvements in Refuse Burners, of which the following is a specification, reference being had to the accompanying drawing.

10 My invention relates to refuse burners, particularly designed for consuming mill waste or refuse about saw mills, and has for its object the production of a device of that kind which is cheap in construction 15 and economical as well as efficient in operation.

My burner is especially designed and adapted to promote complete combustion of material supplied to it to be consumed in 20 such manner as to prohibit any escape of sparks that might otherwise spread conflagration.

At the same time provision is made for keeping the outer wall or shell of the burner cool to a degree that will enable it to carry a coat of paint without deterioration 25 thereof from the heat of the internal fire.

What constitutes my invention will be hereinafter specified in detail and succinctly 30 set forth in the appended claims.

In the accompanying drawing which constitutes a part of this specification,

Fig. I is a side elevation, partially broken away, of my invention in present 35 preferred form of embodiment.

Fig. II is a top plan view of the same complete.

Referring to the numerals on the drawing 40 1 indicates the ground line of a concrete or other foundation 2 that may be set into or erected upon the ground as preferred. The foundation preferably affords support for the entire superstructure with whose transverse shape it corresponds, the 45 shape of both shown in the drawing being circular.

Upon the foundation 2 is erected in close 50 juxtaposition therewith an outside wall 3 terminating in an extension 4 that is preferably cylindrical in shape. An intermediate foraminous zone 5 is preferably provided as part of the extension 4 of the shell consisting of the walls 3 and 4, and is preferably introduced at the lower end of the 55 wall 4 adjacent to the top of the wall 3.

The walls 3 and 4 may be made of any suitable material, preferably sheet metal plates united in overlapping joints 6, or any other preferred construction, and the zone 5 is preferably of suitable wire mesh construction. The shell is preferably supported upon a suitable skeleton or frame work represented by uprights 7 of channel iron having footings in the foundation 2 and riveted or otherwise secured to the 60 plates composing the shell.

Within the lower portion of the shell defined by the wall 3, I provide a truncately conical member 8 preferably constructed after the manner of the shell and comprising legs 10 which preferably have outwardly deflected feet 11 embedded in the foundation 2, though the manner of supporting the legs upon the ground is merely a matter of preference. The construction 70 shown and described is preferred because it affords support for the entire superstructure 75 of my device upon the same foundation.

The member 8 is disposed within the wall 3 of the shell in such manner as to bring 80 its lower edge 12 well above the ground line 1 and its upper edge 14 above the top of the zone 5 with a clear space all around it between its outer surface and the inner surface of the wall 3. In the drawing the 85 angle of inclination of the wall 3 is substantially the same as that of the member 8, but it may be varied if preferred, and particularly with a view of enlarging the air space between the top of the member 8 90 and the shell surrounding it.

The top of the cylinder 4 may be, and preferably is, entirely uncovered and unobstructed. The member 8 is open throughout its length from its lower edge 12 to its 95 upper edge 14.

15 indicates any suitable or preferred conveyor or delivery mechanism for discharging refuse to be burned, into the interior of the member 8. It is shown as introduced 100 through the cylinder 4 so as to discharge into the member 8 from above, but the point of its introduction is immaterial and may be varied at will, provided only, that the member 15 be adapted to discharge within 105 the member 8 at a convenient point for effecting combustion of the material so delivered.

16 indicates a pile of combustible material which is by the member 15 deposited in con- 110

tinuing discharge upon the ground 1 midway of the surrounding shell and superposed member 8.

No special provision is necessary for accommodation of the combustibles 16, though the space circumscribed by the foundation 2 may be denominated a hearth 18 since it affords a place for burning the combustibles 16. A transverse tunnel or trench 19 surrounded by a grate 20 is preferably provided below the ground line. It communicates through one side of the foundation 2 with the middle portion of the hearth 18 from below, the purpose of the tunnel 19 being to afford means for removing ashes as they accumulate.

The object of my invention being, as has been specified, twofold, namely to effect combustion of refuse and to effect it in such degree of perfection as to avoid the discharge of sparks, in considering the operation of my device the means by which both those objects are attained should be observed. Combustion to an entirely satisfactory degree may be obtained within the open top shell supported against the ground by a flared base, represented by the wall 3, since the flared base directs an ascending current of heated air towards the vertical central axis of the cylinder 4 and at the same time creates a descending current of air around the inside of the cylinder which is sufficient for the support of combustion upon the hearth 18, although contribution of air for the support of initial combustion may be had through the tunnel 19.

The introduction of the foraminous zone 5 affords additional supply of air to the interior of the shell.

The member 8 within the shell acts like a nozzle to focus the upward discharge of the products of combustion from the hearth 18 below the top of the cylinder 4, with the effect of producing a whirling annulus of air above the edge 14 of the member 8 and between it and the interior of the cylinder 4, due to the conflict between the aforesaid ascending and descending currents of air. The flared base defined by the wall 3 might be used alone. It is also nozzle-like and the result would be similar if the member 8 were omitted, but the focus of its discharge would be higher within the cylinder 4. The effect of the addition of the member 8 therefore is to convert the space between the walls 3 and 8 into an air intake only, and to lower the focal point and to accentuate the action of the whirling annulus of air within the cylinder 4, with the result of catching any partly burned heavy products of combustion which might produce sparks and precipitating them around the outside of the hearth 18 towards the outer edge of the wall 3.

The angle of inclination of the outer face 65 of the member 8 is such as to facilitate the

precipitation referred to. With or without the member 8, the descending currents of outside air against the inner face of the shell tend to cool it, but the presence of the member 8 affords a double wall to the flared 70 base of the burner and thereby means to effectually protect the wall 3 at points in close proximity to the heat of combustion. Consequently it is practicable, in the preferred form of embodiment of my invention 75 shown in the drawing, to keep the wall 3 so cooled at all times as to enable it to carry on the outside a protective coating of ordinary paint, which is desirable in structures exposed to the weather as mine is.

The presence of the foraminous zone 5 in the shell is especially desirable in the complete form of embodiment of my invention comprising the member 8, and when used in connection therewith it is preferably disposed below the upper edge 14 of the member 8 as shown in Fig. 1 of the drawing.

The cylindrical shape of the extension 4 is preferred because of its simplicity and comparative economy of construction, but it 90 may be modified in a variety of ways without departing from the scope of my invention.

In the drawing the base 3 of the shell is shown as meeting the top of the foundation 2 or in other words the surface of the ground or hearth at an acute angle. If preferred the said angle of inclination may be changed or the point of the angle may be filled in to eliminate the sharpness of the angle. 100

What I claim is:

1. A refuse burner comprising a hearth a shell having an open top and a flared base surmounting and surrounding the hearth and in closed juxtaposition thereto, in combination with a foraminous intermediate zone in the shell. 105

2. In a refuse burner, the combination with a hearth, and a hollow shell having an open top and a flared base surmounting the hearth and in closed juxtaposition thereto, of a hollow member, supported within and spaced from the wall of the shell and raised above the hearth, the upper rim of said member being disposed below the rim of the open top of the shell. 110

3. In a refuse burner, the combination with a hearth, a hollow shell, and an extension thereof open at top and bottom, and having a flared base surmounting the hearth 120 and in closed juxtaposition thereto, of a hollow member supported within and spaced from the wall of the shell, and raised above the hearth, its upper rim being disposed within the extension of the shell, and a foraminous intermediate zone intermediately disposed in the shell extension. 125

4. In a refuse burner, an outside wall closed substantially on all sides except on its top, in combination with an inside hollow 130

imperforate member, open at its top and bottom and spaced all around and above and below from the said outside wall so as to enable it, in operation, to effect intake of atmospheric air through said open top of the burner for the support of the operative combustion within the burner, and also to effect delivery of the products of said combustion medially within the burner towards the place 10 of final discharge through the open top of the burner.

5. In a refuse burner, an outside wall closed substantially on all sides except its top, in combination with an inside hollow 15 member open at its top and bottom, spaced on all sides from the said outside wall, and located entirely within the outside wall

whereby combustion supported in operation within the inside member will maintain at the same time within the burner a descending outside current of atmospheric air and an ascending inside current of the products of combustion, the descending outside current making contact with the inside ascending current and constituting a sheath there- 20 for with the effect described. 25

In testimony whereof, I have hereunto set my hand in the presence of two subscribing witnesses.

JAMES T. STODDARD.
